FOREIGN PATENT DOCUMENTS

GB 2268869 1/1994

Primary Examiner — Susan Moon Lee(74) *Attorney, Agent, or Firm* — Womble Carlyle Sandridge & Rice, LLP(57) **CLAIM**

The ornamental design for a bird feeder, as shown and described.

DESCRIPTION

FIG. 1 is a perspective view of a bird feeder in accordance with a first embodiment of the present invention; FIG. 2 is a front elevation view of the bird feeder of FIG. 1; FIG. 3 is a right elevation view of the bird feeder of FIG. 1; FIG. 4 is a rear elevation view of the bird feeder of FIG. 1; FIG. 5 is a left elevation view of the bird feeder of FIG. 1; FIG. 6 is a top plan view of the bird feeder of FIG. 1; FIG. 7 is a bottom plan view of the bird feeder of FIG. 1; FIG. 8 is a perspective view of a bird feeder in accordance with a second embodiment of the present invention; FIG. 9 is a front elevation view of the bird feeder of FIG. 8; FIG. 10 is a right elevation view of the bird feeder of FIG. 8; FIG. 11 is a rear elevation view of the bird feeder of FIG. 8; FIG. 12 is a left elevation view of the bird feeder of FIG. 8; FIG. 13 is a top plan view of the bird feeder of FIG. 8; and, FIG. 14 is a bottom plan view of the bird feeder of FIG. 8. The broken lines shown herein are for illustrative purposes and form no part of the claimed design.
